United States Patent Office

Des. 213,312

Patented Feb. 18, 1969

213,312

TRACTOR

Bruce L. Renquist, Racine, Wis., assignor to J. I. Case
Company, Racine, Wis., a corporation of Wisconsin

Filed Jan. 15, 1968, Ser. No. 10,161

Term of patent 14 years

U.S. Cl. D14—3

Int. Cl. D12—09

FIG. 1

FIG. 2

FIG. 4

FIG. 5

FIG. 3

FIGURE 1 is a perspective of the tractor of my invention;

FIGURE 2 is a side elevational view of one side of the tractor;

FIGURE 3 is a side elevational view of the opposite side of the tractor;

FIGURE 4 is a view of one end of the tractor; and

FIGURE 5 is an end view of the opposite end of the tractor.

The elements shown in broken lines are only included for illustrative purposes.

I claim:

The ornamental design for a tractor, as shown and described.
